[57] **CLAIM**

The ornamental design for a protective housing for a needled syringe, as shown and described.

DESCRIPTION

FIG. 1 is a perspective view of a protective housing for a needled syringe showing my new design, the broken line showing of needled syringe is for illustrative purposes only and forms no part of the claimed; FIG. 2 is a top plan view thereof, the bottom plan view being a mirror image thereto;

FIG. 3 is a front elevational view thereof, the rear elevational view being a mirror image thereof;

FIG. 4 is a right side elevational view of the design shown in FIG. 1; and,

FIG. 5 is a left side elevation of the design shown in FIG. 1.

FIG. 1

FIG. 4

FIG. 2

FIG. 3

FIG. 5
